PIN SPOTTER AND PINS GAME DEVICE
 Holger Pedersen, 4736 N. Winchester, Chicago 40, Ill.
 Filed Apr. 3, 1961, Ser. No. 100,164
 2 Claims. (Cl. 273—42)

This invention relates to amusement devices and more specifically to a miniature bowling game.

Various simulations of bowling games have been made. In general these have been cheaply fashioned and do not in the least provide a close enough reality to the game to stimulate adult interest. Miniaturization of itself does not suggest participation.

With these deficiencies in mind, the invention contemplates the provision of novel improvisations which enhance the game without radically changing its basic concepts.

The invention comprehends the provision of a novel pin spotter having a novel interlock with the alley such that the pin spotter may be readily mounted upon and removed from the alley.

Another object of the invention is to provide an alley structure which incorporates a shock absorbing backstop for the ball and pins, the backstop having a forward nonmetallic panel and a rear metal plate, the panel and plate being held pendulously lightly together by embracing legs of a torsion spring from a common transverse hinge shaft mounted across the side panels of the pin-receiving bay at the rear end of the alley.

Another object of the invention is to provide a novel arrangement of the backstop such that it divides the rear of the alley into a bay and is swingable upwardly away from a pin tray therebehind to facilitate an operator reaching under the backstop to clear the downed pins and rake them into the tray.

A further object is to provide a novel guide and support structure for the pin setter from the side walls of the alley one of which also forms an elevated runway for the ball return which terminates at the player end of the alley in an upwardly inclined retarder ramp which merges into a receiver rack.

A still further object of the invention is to devise a novel and efficient pin setting mechanism which comprises a pair of superposed templets in the form of apertured panels, the upper panel having its pin-receiving apertures offset from the corresponding apertures in the lower panel which are arranged in a pin locating arrangement, and the lower panel having inclined ramps upon which the pins are adapted to be laid in a downwardly sloping position and the apertures in the upper plate being arranged to admit the pins in partially prone position and having back edges and side edges which confine the pin which is nested in the aperture on the ramp, the edges serving to guide and move the pin down the ramp into an associated vertical opening in the lower panel whereupon the pin drops through the vertical opening onto the playing surface of the alley therebeneath.

A further object is to devise a novel pin spotter which easily sets the pins and which may be lowered and elevated with respect to the pins upon the alley without disturbing their setting.

These and other objects and advantages inherent in and encompassed by the invention will become more readily apparent from the specification and the drawings wherein:

FIGURE 1 is a broken apart plan view of the novel alley;

FIGURE 2 is a side elevational view of the structure shown in FIGURE 1;

FIGURE 3 is an enlarged vertical longitudinal section taken essentially on line 3—3 of FIGURE 1;

2

FIGURE 4 is a vertical cross-sectional view taken substantially on the line 4—4 of FIGURE 3;

FIGURE 5 is an enlarged fragmentary plan view of a portion of the alley and pin setter shown in FIGURE 3;

FIGURE 6 is a longitudinal sectional view comparable to FIGURE 3 illustrating the pin set position and partial elevation in phantom of the setting mechanism; and

FIGURE 7 illustrates in longitudinal section similar to FIGURE 6 a modified form of the pin setting mechanism.

Description of FIGURES 1-6

Describing the invention in detail the game or recreational device generally designated 2 comprises an alley 3 having a run-up area 4 which is divided from the runway 5 by a foul guard 6 in the form of an inverted U-shaped stop having a transverse upper bight 7 and dependent legs 8 which are impaled into the flooring 9 in the area 4. The legs 8 are in advance of and in alignment with the gutters 10 which flank the playing area 5. The gutters open into a bay 11 at the rear end 12 of the alley. The bay 11 is formed by vertical extensions 13, 13 of the longitudinal vertical side walls 14, 14 of the unit 3 and by a transverse vertical backstop 15 which is mounted along its upper edge on a hinge pin or shaft 16 extending normal to the extensions 13 adjacent to their upper edges at substantial elevation above the plane of the playing area. The shaft 16 mounts a pair of axially spaced hinges 17, 17 which are connected to the upper portion of an inertia mass in the form of a heavy, flat, vertical metal plate 18 which has its upper edge 20 along the underside of shaft 16 and its lower edge 21 adjacent to but slightly spaced from the bottom 22 of the bay which is depressed below the plane of the playing area 5. The lateral edges 23, 23 of the plate 18 oppose and are closely spaced from the respective extensions 13. The front or forward side of the backstop comprises a "Masonite" or plastic or other nonmetallic panel 24 which is preferably codimensional with plate 18 and is held thereagainst by a torsion spring 25 which has its coil loop 26 sleeved about shaft 16 and its legs 27 and 28 embracing the panels 18 and 24, through a fabric-plastic or leather facing 29.

The extensions 13, 13 are provided rearwardly of the backstop 15 with inwardly projecting vertical abutments 30, 30 which are faced with cushion pads 31, 31 in opposing and engaging relation with the back side of the backstop 15 adjacent to its lateral edges. Thus when a ball 33 is hurled against the backstop the front flap 24 swings against the heavy plate 18 which resists rearward movement and partially absorbs the blow. Any force which transcends this action swings the backstop against the cushions which reacting against their supporting abutments further absorb the shock.

A feature of this invention is in the provision of a pin tray 35 rearwardly of the backstop 15 and as a continuation of the alley structure in that the side walls 14 as well as the bottom wall 22 continue rearwardly beyond the backstop 15 and merge with an upwardly and rearwardly inclined back wall 36 which in providing a diagonal surface area facilitates scooping out of the pins 37 by the players who reach beneath the backstop into the bay by swinging the backstop upwardly and forwardly to retrieve any downed pins whereupon by raking the pins rearwardly into the tray the player's hand is removed accommodating the backstop to swing gravitationally downwardly to operative position.

The interiors of the extensions 13, 13 are lined with combination pin rack or spotter guide and support means 39, 39 each being in the form of an embossed U-shaped bracket having a pair of upright portions 40, 40 defining a vertical slot 40' with opposing substantially parallel

generally vertical intermediate and lower margins 41, 41 which flare into upwardly diverging upper edges 42, 42 to facilitate admittance and entry of the guide and positioning means 43 of a pin spotter generally designated 45, said means 43 taking the form of a pin or shaft which closely fits between edges 41, 41 and seats upon the closing bottom edge 46 of the guide slot.

The pin setting mechanism 45 is a planar structure of less width than the distance between the extensions 13, 13 and is provided with two vertical side members 47, 47 which have rear end portions projecting rearwardly beyond the body 48 of the mechanism and fasten to the shaft 43 substantially medially between its ends. The rear end portions of the side members 47 form feet 50 which extend below the bottom side 51 of the body 48 and have flat horizontal lower edges 52 which seat upon the support surface 52' of any support.

The body portion 48 is set substantially medially between the effective top and bottom edges of the side members and spaced above the alley surface 5 and is joined along its lateral sides with the side members. The front end 53 of the body 48 is provided with a dependent rest 54 which seats at its lower edge 55 upon the surface 5 and with the shaft 43 supports the body 48 in a substantially level position. The body is provided with ten vertical cylindrical openings 56 arranged in a triangular pattern following a typical bowling arrangement with one pin in front at the apex, two behind, three behind those and four behind those. The upper side 57 of the body is notched behind each hole to provide a rearwardly and upwardly sloping ramp 58 which leads at its forward lower discharge end into the associated opening 56.

As best seen in FIGURE 3, the ramp or guide trough 58 admits an intermediate cylindrical profile 59 of the lower end portion 60 of pin 37, said portion 60 having a downwardly tapered lower end portion 61 below section 59 and an upwardly tapered upper end part 62 above portion 59, the section 62 merging into a cylindrical upper stem portion 63 which is of approximately the diameter of the upper end of part 62.

In the receiving position of the set-up mechanism the pins are set onto respective ramps and incline upwardly and rearwardly with the conical bottom portion 61 entered into a narrowed forward end slot portion 64 of an associated slot 65 in the plate portion 66 of the actuator generally designated 67.

The slot portion 64 merges into a widened slot portion 68 which has vertical side margins 69, 69 closely embracing the cylindrical part 59 in guiding engagement therewith. The slot portion 64 is defined by an arcuate rear margin 70 which is contoured to admit the upper portion 62 of the lower end part 60, portion 62 bearing as at 71 intermediate its ends against the upper surface 72 of the actuator plate 66. Thus it will be readily apparent that the openings in the actuator plate and the openings in the base are horizontally offset and that actuation of the plate 66 forwardly advances the pins therewith while vertically aligning the openings 56, 65. The flat base 73 of the pin extends below the plate and is entered into the upper part of the associated opening 56 and upon forward movement by the actuator, the pin slides off the associated incline 58 and tends to right itself and drops through the opening 56 onto the playing surface 5.

The plate 66 is slidable upon the top surface 57 of the body portion 48 and is guided along its lateral edges between the side members 47, 47. The member 66 is held against the body portion by the heads 75 of screws 76 which extend through elongated slots 77 in plate 66 and are screwed into the base 48.

The plate 66 is biased to retracted position by a pair of tension springs 78, 78 which lay within longitudinal grooves 79, 79 in the base adjacent to the side members 47, 47, each spring having one end hooked to a fixed anchor screw 80 located in the associated groove 79 and

into the base 48 adjacent to its rear extremity 81 and the other end of the spring being secured to an anchor screw 82 secured to the plate 66 and projecting into the related groove 79 adjacent to the forward end 53 of the body.

In order to condition the apparatus for play, the bottom 22 of the alley structure is provided with leveling bolts 84 which are threaded into the bottom 22 along the lateral edges thereof to level the playing surface. The 10 pin spotting tray is located upon the alley by inserting the ends of the cross shaft 43 into the slots 40' of the guides 39 and lowering the tray until bottomed and rest 54 sits upon surface 5. The pins are then inserted upon the ramps 58 as seen in FIGURES 3 and 5. Then the 15 actuator 66 is moved forwardly manually by the operator's finger 85 (FIG. 6) as shown by the arrow until the pins drop through the opening 56 and seat upon the playing surface 5. The actuator plate is released and since the narrow upper portions clear the narrow slot portion 64, the spotter is lifted off the pins 37 and the 20 device is ready for play.

One player rolls the ball 33 from the area 4 onto the alley surface 5. If the ball does not gutter, it will strike the pins. The fallen pins are gathered by the player 25 who acts as pin boy, by reaching under the backboard 15 and raking them into the tray 35.

The ball 33 is returned to the player on the ball return track generally designated 86 which comprises a groove formed in the upper edge of a side member extensions 13, and contiguous side walls 14. The ball is rolled in groove section 87 in member 13 and proceeds down the ramp 88, on the forward edges of extensions 13 and along the groove sections 89 on wall 14 and up the ramp 90 on extension 91 of wall 14 and onto a 35 slightly inclined groove portion 92 on the upper edge of portion 91 which is located along the player area.

Play is followed as in regulation bowling. The pins are reset as hereinbefore explained and the scoring proceeds as in regular bowling.

Description of FIGURE 7

The structure of FIGURE 7 is comparable to that shown in the previous embodiment and like parts are identified by corresponding numerals. In the present 45 modification, the plate 66 is guided diagonally upwardly and forwardly in diagonal upwardly and forwardly sloping transverse slots 106, 101 in the side members 47, 47 by means of pins or guides 102 and 103 which extend laterally outwardly of the sides of the plate 66 into respective slots and guided between the margins thereof. This construction obviates the necessity for great accuracy in mating the plate 66 and body 48 and eliminates the springs and by pulling forwardly on the plate 66 it is caused to move upwardly which tends to aid in tipping the pins from their reclined positions to upright 55 position. Gravity brings the plate 66 down.

The foregoing description is intended to disclose preferred embodiments of the invention and is not in any way intended as a limitation and it will be readily understood that other forms of the invention will become readily apparent to those skilled in the art within the scope of the appended claims.

What is claimed is:

1. In combination, a pin spotter having front and rear ends comprising upper and lower generally horizontal relatively movable plate-like members, said lower member having a plurality of cylindrical openings arranged in a conventional bowling formation, said upper member having similarly arranged elongated apertures, each aperture having a wide rear portion and a narrow front portion in vertical alignment with the respective opening in the lower member, said lower member having an upper side with a ramp face behind each cylindrical opening and sloping downwardly into the upper end thereof, said 65 upper member having a ramp surface within the rear

end of each aperture sloping downwardly forwardly toward the associated cylindrical opening and having substantially vertical lateral edges with forward ends curving into a semicylindrical notch, said notch defining the narrow front portion of the apertures, and pins disposed in reclining position preparatory to spotting, each pin comprising a fusiform shaped body having a lower end base, a downwardly tapered lower end portion projecting into the upper end of the associated cylindrical opening, a cylindrical intermediate portion of a diameter closely approximating that of the cylindrical openings in the lower member confined in the reclining position between said lateral edges of the respective aperture and seated upon the respective ramp face, the body of each pin having an upper upwardly tapered portion abutting in the reclining position of the pin against the associated ramp surface, each ramp surface attendant to movement of the upper member toward said forward end of the device moving the related pin forwardly and through engagement of the lower end of the body of the pin with the surface of the cylindrical opening tipping the pin from reclining to upright position coincidental with said lower tapered portion guiding the pin into the associated cylindrical opening in the lower member to enter the cylindrical portion of the pin therein, each pin having a cylindrical stem projecting upwardly from the body, said stem complementally fitting into the semicylindrical notch in the associated aperture, portions of said upper member at opposite sides of each notch overlapping the body of the pin therebelow upon the latter being vertically positioned to prevent its withdrawal and said cylindrical stem being of substantially uniform section throughout its length and having a nonbulbous upper end

10

5 2. The invention according to claim 1 and said members relatively movable in a direction transaxially of the openings in the lower member, and spring means reactively engaged with said members biasing them to a position offsetting said openings with respect to said apertures wherein the semicylindrical notches of the apertures are vertically aligned with the respective openings.
